UNITED STATES PATENT OFFICE.

JOEL MCKENNEY, OF BOSTON, MASSACHUSETTS, ASSIGNOR OF ONE-HALF TO
W. O. ROBSON, OF SAME PLACE, AND JOHN M. FRENCH, OF CHELSEA,
MASSACHUSETTS.

BRIDLE-BIT.

SPECIFICATION forming part of Letters Patent No. 402,608, dated May 7, 1889.

Application filed August 20, 1888. Serial No. 283,186. (No model.)

To all whom it may concern:

Be it known that I, JOEL MCKENNEY, of Boston, in the county of Suffolk and State of Massachusetts, have invented certain new and useful Improvements in Snaffles, of which the following is a specification.

My invention relates to snaffles or bridle-bits, and has for its object the provision of a snaffle which may be used with entire subduing and controlling effect in the work of "breaking" and effort of controlling untamed or vicious horses.

My invention consists, broadly, of a snaffle consisting of two bars jointed together by means of a link connected with each bar at an appreciable distance from its meeting end with the other bar, whereby when a pull or jerk is given to the reins attached to rings connected with the outer ends of the snaffle, or two bars composing the snaffle, the inner ends of the latter will be thrown upward or outward, and thus so act as to punish the horse and confine his attention entirely to the influence of the snaffle or bit.

Reference is to be had to the accompanying drawings, and to the letters of reference marked thereon, forming a part of this specification, of which drawings—

Figure 1 is a view of the head and neck of a horse, showing one of the desirable ways of arranging a bridle and reins in the use of my invention. Fig. 2 is a perspective view of my improved snaffle. Fig. 3 is a front view of the same.

The same letters of reference designate the same parts in all of the views.

As has already been stated, my improved snaffle is composed of two bars or pieces, *a a*, jointed together by means of a link, *b*, which is connected with each bar *a a*, as at *c*, an appreciable distance from its meeting end with the other bar.

d designates rings, preferably (though not necessarily) elongated, as shown, with which

the branching straps *e* of the overdraw *f*, as 45 also the cheek-straps *g* of the bridle, may be connected.

h designates rings pivotally connected with the outer ends of the bars *a a*, comprising the snaffle or bit, to which the driving-reins *i* may 50 be attached, as shown.

With this construction, as long as the horse is well-behaved and gentle in manner, the bit may be used without the least punishing effect and without the least inconvenience or 55 discomfort to the horse; but should he become unruly and attempt to kick or run (one of the first motions of which action is the throwing down of the head) the overdraw, pulling on the rings *d*, will operate to throw the inner 60 ends, *j j*, of the bars *a a*, comprising the bit, upward against the roof of the animal's mouth, and so punish him as to take his attention from his vicious intent. So, also, if the driver should draw on the reins *i*, the effect would 65 be to throw the ends *j j* upward, as before described, with the result as explained.

It is obvious that changes may be made in the form and arrangement of parts comprising my invention without departing from the 70 nature or spirit thereof.

What I claim is—

The herein-described snaffle or bit, consisting of two bars or pieces, the inner ends of which meet or nearly meet, said bars or pieces 75 being jointed together by means of a link connected therewith at an appreciable distance beyond the meeting ends, all substantially as and for the purposes described.

In testimony whereof I have signed my name 80 to this specification, in the presence of two subscribing witnesses, this 14th day of August, A. D. 1888.

JOEL MCKENNEY.

Witnesses:

ARTHUR W. CROSSLEY,
CLARA F. SHAW.
